PILE CASING CUTTERS

Lee M. Boughton, Kathan Road, Brewerton, N.Y., assignor of one-half to Philip Hillsberg and Maurice H. Sharp, Syracuse, N.Y.

Filed June 26, 1959, Ser. No. 823,135

8 Claims. (Cl. 83—191)

This invention relates to novel devices for cutting pile casings at excavation level which have been driven into the ground, and more particularly to cutters of this kind which operate inside of pile casings.

The primary object of the invention is to provide more efficient and effective cutters of the kind indicated, which are characterized by radially acting cutter plates, which are operated, either mechanically or hydraulically, to cut through the side walls of pile casings, after the cutters have been lowered into the casings to the desired levels and are controlled from outside of the casings.

Another object of the invention is to provide cutters of the character indicated above, which are compact and uncomplicated in construction, being composed of a small number of simple and easily assembled parts.

Other important objects and advantageous features of the invention will be apparent from the following description and the accompanying drawings, wherein, for purposes of illustration only, a specific form of the invention is set forth in detail.

In the drawings:

FIGURE 1 is a top plan view of a mechanically operated cutter device of the invention;

FIGURE 2 is a side elevation thereof, and a driving hammer interior parts, being indicated in phantom lines;

FIGURE 3 is a fragmentary vertical transverse section taken on the line 3—3 of FIGURE 2;

FIGURE 4 is a horizontal section taken on the line 4—4 of FIGURE 3;

FIGURE 5 is a section similar to FIGURE 3, but showing the device in compressed operative position inside of a pile casing, the latter being shown in phantom lines;

FIGURE 6 is a fragmentary transverse vertical section, taken through a hydraulically operated device of the invention; and

FIGURE 7 is a top plan view of FIGURE 6.

Referring in detail to the drawings, wherein like and related numerals designate like and related parts throughout the several views, and first to FIGURES 1 to 5, the device therein shown and generally designated 10, comprises a vertically elongated tubular barrel 12, preferably of cylindrical cross section and having an open upper end 14. The lower end of the barrel 12 is suitably fixed, as by welding, to the center of a circular plate or disc 16, which is substantially larger in diameter than the barrel, but is slightly smaller in diameter than smallest diameter side casing C with which the device is to be used, and whose peripheral edge 18 acts to engage the casing side wall 20 and center the device in the casing C.

Resting slidably upon the flat upper surface 22 of the plate 16 around the outside of the barrel 12, is a plurality of pairs of diametrically opposed cutter plates 24, here shown as two pairs of similar, sector-shaped cutter plates, whose convergent side edges 26 are in touching and in stop relation to each other in the inoperative or retracted positions of the cutter plates, as seen in FIGURE 1. The assembly of the cutter plates 24 forms, in effect, in the retracted positions thereof, an annulus which is slightly smaller in diameter than the disc 16, so that the radially outwardly facing arcuate and downwardly bevelled cutting edges 28 of the cutter plates are then at, or slightly inwardly of, the peripheral edge 18 of the disc 16, so

2

as to avoid abrasive contact thereof with a pile casing side wall 20, when the device 10 is lowered into and withdrawn out of a pile casing, such as a cable on a winch on the pile driver, running over a pulley on the pile driver head. Suitable means (not shown), secured to ears 29 on the upper end of the barrel 12, is employed for positioning the device at the desired height in a pile casing.

Operating mechanism for the cutter plates 24 comprises a movable pressure head 30, sliding within the lower part of the barrel 12 and connected to the plates 24 by downwardly and outwardly declining, radially disposed dual links 32. The pressure head 30 comprises a circular top plate 34, of a diameter to slide vertically and guidedly in the barrel 12, and a cruciform 36, fixed to and depending from the top plate and having four radial, equally spaced vertical webs 38, through each of which extends a headed pivot pin 40. On the pin 40, at opposite sides of the webs 38, are securely pivoted the elevated inward ends of the links 42 of the dual links 32.

Centered upstanding lugs 43 on the cutter plates 24, located outside of the barrel 12, carry headed pivot pins 44, on which the depressed outer ends of the links 42 are pivoted, at opposite sides of the lugs 43. The dual links 32 work through vertically elongated slots 46 in the lower part of the side wall 48 of the barrel 12.

Pressure head elevating means, whose operation serves to retract the cutter plates 24, after operation thereof, comprises a vertical helical expansion spring 50 which is circumposed on a column of vertical rods 52 which are individually fixed, at their lower ends, to a block 54 fixed on the upper surface of the disc 16, as seen in FIGURE 3. The spring 50 is compressed between the cruciform 36 and the disc 16, and normally holds the cutter assembly pressure head 30 in its elevated position, wherein the cutter plates 24 are fully retracted. The webs 38 of the cruciform 36 pass between the rods 52, when the pressure head 34 descends.

In order to operate the cutter plates 24 outwardly, so as to cut through the side wall 20 of a pile casing C, in which the device 10 is suspended, a hammer 56, operated from the upper end of the casing C, by suitable means (not shown), is dropped in the barrel 12, so that the hammer strikes and depresses the pressure head 30, against the resistance of the spring 50, as shown in FIGURE 5. Then the hammer 56 is elevated off the pressure head 30, whereat the spring 50 expands and retracts the cutter plates 24. These operations are repeated, if necessary, until the casing C is cut off, at the desired level, as at the ground level of an excavation lower than that from which the casing was originally driven.

The hydraulic form of the invention, shown in FIGURES 6 and 7, and generally designated 10a, has a barrel 12a and a cutter mechanism similar to those of FIGURES 1 to 5, but devoid of a retracting spring, and a fixed or upper pressure head 58 is provided in the barrel 12a above the movable or lower pressure head 30a, in order to operatively accommodate an expandable and contractible hydraulic jack 60. The jack 60 performs the functions of the hammer 56 and the spring 50 of FIGURES 1 to 5.

The fixed pressure head 58 can comprise a hydraulic jack base plate 62, which is held removably in place, at a level spaced above the lower pressure head 30a, by means of a lower pair of chordally arranged bolts 64, extending across the interior of the barrel 12a and through its side wall 40a, upon which the base plate 62 rests, and an upper pair of chordally arranged bolts 64' similarly arranged in the barrel 12a, and which extend crosswise of the lower bolts 64 and bear upon the upper side of the base plate 62. The body 66 of the jack 60 depends from the base plate 62, and a piston rod 68 extends downwardly from the body 66, and is rigidly and

fixedly secured to the center of the top plate 34a of the lower pressure head 30a, by suitable means, as indicated at 70. A suitable hydraulic hose 72 leads from the jack body 66, out of the barrel 12a through a hole 74 provided in its side wall 40a and upwardly to the upper end of a casing C, in which the device 10A is being used, and is thereat connected to a suitable hydraulic ram (not shown) which can be operated to both expand and contract the jack 60, for extending the cutter plates and retracting the cutter plates, respectively.

Although there have been shown and described herein preferred forms of the invention, it is to be understood that the invention is not necessarily confined thereto, and that any change or changes in the structures of and in the relative arrangements of components thereof are contemplated as being within the scope of the invention as defined by the claims appended hereto.

What is claimed is:

1. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a vertically movable pressure head confined in the barrel, and individual links operatively connected to and extending between the pressure head and the cutter plates.

2. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said operating means further comprising retracting spring means acting between said disc and said pressure head for yieldably elevating the pressure head and retracting the cutter plates radially inwardly, and hammer means within the barrel above said pressure head, said hammer means being downwardly engageable with the pressure head to depress the pressure head, against the resistance of said spring means and extend the cutter plates outwardly away from the barrel for cutting the side wall of a pile casing.

3. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said operating means further comprising retracting spring means acting between said disc and said pressure head for yieldably elevating the pressure head and retracting the cutter plates radially inwardly, and hammer means within the barrel above said pressure head, said hammer means being downwardly engageable with the pressure head to depress the pressure head, against the resistance of said spring means and extend the cutter plates outwardly away from the barrel for cutting the side wall of a pile casing, the cutting edges of the cutter plates being protectively positioned within the peripheral edge of the disc in their retracted positions.

4. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said operating means further comprising a fixed pressure head secured in said barrel and spaced above said movable pressure head, and an extensible and contractible hydraulic jack extending between and fixed to the pressure heads.

5. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said operating means further comprising a fixed pressure head secured in said barrel and spaced above said movable pressure head, and an extensible and contractible hydraulic jack extending between and fixed to the pressure heads.

6. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said pressure head having radial webs and said cutter plates having upstanding lugs, said link means extending between the webs and the lugs and being pivoted at related ends thereto, the side wall of said barrel having vertical guide slots through which the link means work.

7. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate radially outward cutting edges, and operating means for the cutter plates comprising a movable pressure head confined in the barrel for vertical movement, and link means operatively connected to and extending between the pressure head and the cutter plates, said pressure head having radial webs and said cutter plates having upstanding lugs, said link means extending between the webs and the lugs and being pivoted at related ends thereto, the side wall of said barrel having vertical guide slots through which the link means work, said link means comprising pairs of links pivoted to opposite sides of the webs and opposite sides of the cutter plate lugs.

8. A pile casing cutter comprising a vertically elongated tubular barrel having an open upper end, a disc fixed concentrically on the lower end of the barrel, said disc being larger in diameter than the barrel and having a peripheral edge to bear guidingly against the interior of a pile casing, cutter plates slidably resting upon the upper surface of the disc, said cutter plates having arcuate

radially outward cutting edges, and operating means for the cutter plates comprising a movable pressure head confined in the barrel for vertical movement, and link means operatively connected to and extending between the pressure head and the cutter plates, said operating means further comprising retracting spring means acting between said disc and said pressure head for yieldably elevating the pressure head and retracting the cutter plates radially inwardly, and hammer means within the barrel above said pressure head, said hammer means being downwardly engageable with the pressure head to depress the

pressure head, against the resistance of said spring means and extend the cutter plates outwardly away from the barrel for cutting the side wall of a pile casing, said spring means comprising a vertical helical spring compressed between the movable pressure head and the disc.
